UNITED STATES PATENT OFFICE.

ALVARO S. KROTZ, OF JANESEVILLE, WISCONSIN, ASSIGNOR TO THE JANESEVILLE MACHINE COMPANY, OF JANESEVILLE, WISCONSIN, A CORPORATION OF WISCONSIN.

CULTIVATOR.

1,413,336.

Specification of Letters Patent. Patented Apr. 18, 1922.

Application filed December 4, 1916. Serial No. 134,970.

To all whom it may concern:

Be it known that I, ALVARO S. KROTZ, a citizen of the United States of America, and resident of Janesville, Rock County, 5 Wisconsin, have invented a certain new and useful Improvement in Cultivators, of which the following is a specification.

My invention relates to cultivating machines of that kind in which the cultivator-gangs are connected with a frame supported by wheels, said frame having a seat for the rider, and in which means are provided for enabling the rider to steer the machine to the right or the left, as is often necessary in 10 different kinds of work, such as the cultivation of corn planted in rows.

Generally stated, the object of my invention is to provide an improved construction and arrangement whereby the rider may 20 have foot-control over the cultivator-gangs, so that either gang can be swerved to one side, and whereby this foot-control will be accompanied by a swerving of the seat in the other direction, causing the wheels to 25 skew relatively to the tongue or pole, and thus permitting the rider to very easily and quickly control the machine for the purpose of steering it to the right or the left and thereby keeping the gangs from running 30 over the corn.

It is also an object to provide certain details and features of construction and combinations tending to increase the general efficiency and desirability of a cultivator 35 having a seat-controlled steering-arrangement of this particular character.

To the foregoing and other useful ends, my invention consists in matters hereinafter set forth and claimed.

40 In the accompanying drawings:—

Fig. 1 is a plan of a riding cultivator embodying the principles of my invention.

Fig. 2 is a similar view showing the operation of the seat-controlled steering-arrangement by which the wheels are skewed 45 relatively to the tongue or pole.

Fig. 3 is a side elevation of said cultivator, showing the near wheel removed for convenience of illustration.

50 Fig. 4 is a front elevation of said cultivator.

Fig. 5 is an enlarged detail section on line 5—5 in Fig. 1.

Fig. 6 is an enlarged detail section on line 6—6 in Fig. 1. 55

Fig. 7 is an enlarged detail section on line 7—7 in Fig. 3.

Fig. 8 is an enlarged detail section on line 8—8 in Fig. 7.

As thus illustrated, my invention comprises a gang-arch A consisting, preferably, of a round bar bent approximately into the shape of an arch, and having its lower ends *a* bent outward to provide horizontal portions to which the gangs B are connected. 60 As shown, each gang comprises an ordinary gang-bar *b* to which are secured the cultivator-shovels 1 of any suitable form or character. The gang-bars *b* are secured by vertical pivots 2 upon the castings 3 which are 70 rotatably mounted upon the horizontal end portions *a* of the gang-arch, so that each gang can swing up and down at its rear end, by reason of its pivotal connection with the gang-arch, and can also swing sidewise 75 about its vertical pivot 2, in a manner that will be readily understood. Said gang-arch has its upper portion connected by a U-bolt 4 with the under side of the rear portion of the tongue or pole C, and has its 80 lower end portions *a* connected by braces 5 with a point some distance forward on said tongue or pole. An arch-shaped axle D is provided at opposite ends with the supporting wheels *d*, and the upper portion of this 85 axle is mounted to turn in bearings 6 secured to the rear end of the frame-bars E, which latter constitute the main frame and are connected together by a yoke *e* which encircles the tongue or pole and is provided 90 with a vertical pivot 7, which latter consists of a bolt passing downward through said tongue or pole. Brackets 8 are secured to the gang-arch near the lower ends of the vertical portions thereof, and brackets 9 are 95 secured to the sides of the frame-bars E, which latter constitute the main frame of the machine. Links 10, consisting of rods with their ends bent at an angle, connect the brackets 8 with the brackets 9, these links being disposed approximately in vertical positions at opposite sides of the machine, and permitting said main frame to swing sidewise relatively to the gang-arch. An evener F is secured in place by the pivot 7, and vertical bars *f* are hung on the ends of said

100

105

evener F, which vertical bars are in turn connected at their lower ends by links 11 with the extreme outer ends of the gang-arch. Each bar f has a whiffle-tree 12 suitably connected thereto.

A square rock-shaft G is disposed transversely below the main frame-bars E, and is supported in bearings g secured to said frame. Said shaft is provided with sleeves 13 which turn with the shaft in said bearings, and which are provided with arms 14 connected by pivoted links 15 with the brackets 16 which are secured upon the axle near the lower ends thereof, whereby said 15 axle is braced against turning in the bearings 6 on the rear ends of the main frame. A hand-lever H is secured upon the rock-shaft G and is provided with a hand-operated catch or locking device h to engage 20 the notches in the segment 17 which is rigidly secured to the main frame, so that when this hand-lever is locked in position the axle is rigidly braced by the links 15 which extend forward from the axle to the arms 14 25 on the rock-shaft. The segments I, one at each side of the machine, immediately outside of the frame, are rigid with the sleeves 13, but the two hand-levers i are mounted to turn on the outer ends of the sleeves 13, and 30 are provided with hooks 18 which are connected by the chains 19 with the hooks 20 on the bars b of the cultivator-gangs. The hand-levers i are provided with suitable catches or locking devices 21, which may be 35 of the usual character, to engage the notches of the segments I, so that each hand-lever can be locked in any desired position relatively to its allotted segment. When these hand-levers are raised and lowered, by unlocking them, or either of them, from the segments I, the cultivator-gangs can be raised from the ground. When the hand-lever H is unlocked from its segment 17, the 40 shaft G and the two hand-levers i and the segments I will all be rocked about a horizontal axis, with the result that both gangs will be raised in unison, and the axle D will tilt forward slightly, thus utilizing the weight of the frame and tongue to assist in 45 raising the gangs from the ground. The hand-lever H is preferably provided with a short arm 22, at the rock-shaft G, which arm is connected by a spring 23 with the bracket 24 on the main frame, whereby this 50 spring assists in raising the cultivator-gangs from the ground. Heavy springs 25 are connected between the brackets 26 on the upper portions of the gang-arch A and the brackets 27 which form portions of the connections between the cultivator-gangs and the lower horizontal portions of said gang-arch. These springs 25, therefore, assist in 55 raising the gangs from the ground, and their lifting power can be regulated by adjustment of the connection 28 for the lower end 60

of each spring to any one of the holes 29 in the brackets 27, thereby giving each spring the benefit of either a greater or less leverage in raising the gangs. Horizontal rods 30 are arranged to slide endwise in bracket 70 bearing 31 (which are integral with the hooks 20) on the gang-bars b, with a compression spring 32 at each side of each bracket, so that the endwise movement of these rods in either direction is resisted by springs. 75 The forward ends of these rods 30 are hooked onto the outwardly extending arms 33 which are rigid with the castings 3 on the end portions of the gang-arch. In this way, lateral movement of the gangs is resisted by the springs 32, and after being swerved to one side the gangs then have a tendency to regain their normal positions by reason of the action of said springs. Each gang is provided with a stirrup 34 for the feet of 80 the rider, so that either gang can be pushed or swerved laterally away from the row of corn.

The seat-controlled steering-arrangement comprises the seat-frame J which is of suitable form and construction and is provided with a casting or cross-bar j which is pivoted at 35 upon the top of the axle, so that this seat-frame and axle may skew relatively to each other. (See Fig. 2). The forward 90 end of this frame J is loosely hooked onto the rear end of the tongue or pole C, in any suitable manner, so that said seat-frame may skew about a vertical axis relatively to said pole or tongue. For example, the forward portion of said seat-frame may be provided with a loose link 36 which passes loosely through the eye 37 secured to the rear end of the pole or tongue, and with this arrangement the skewing of the wheels 105 d relatively to the tongue or pole, and the consequent skewing of the seat-frame J relatively to said tongue or pole, is possible without injury to or straining of any of the different parts. A driver's seat 38 is 110 secured upon the rear end of the seat-frame J, which latter extends rearwardly a distance from the top of the axle D, whereby said seat is preferably a little in rear of the wheels and about over the rear ends 115 of the two gangs. With this arrangement, it will be seen, the said frame J is not only a support for the driver's seat, but also is capable of acting as a lever to skew the tongue and wheels relatively to each other; 120 for when the driver uses one foot to thrust one of the gangs in one direction, the reaction of this muscular effort on the part of the driver is exerted against the seat 38 in the opposite direction, so that the frame J 125 then fulcrums at 35 and develops sufficient leverage to forcibly carry the rear end of the tongue or pole to one side in a direction opposite to that in which the seat swings. In other words, if the seat swings to the 130

right (see Fig. 2), the seat-frame J acts as a lever to swing the rear end of the tongue or pole to the left, and, vice versa, when the seat swings to the left the rear end of the tongue or pole swings to the right. It will be seen, however, that the gang-arch A always remains at right angles to the tongue or pole C, and that the axle D always remains at right angles to the main frame formed by the bars E, so that the tongue and gang-arch constitute practically one rigid element, while the axle and the main frame constitute another rigid element, the two elements being pivotally connected together at 7, and the seat and its frame J constitute still another pivoted element which exercises a control over the other two elements to steer the machine to the right or left. In effect, the forward end of the tongue or pole C pivots on the neck yoke of the team, so that it is comparatively easy to swing the rear end of the tongue C to one side or the other, by the lever formed by the seat-frame J, thus causing the rear axle and the main frame to skew relatively to the tongue or pole about the vertical axis provided by the pivot 7, the gang-arch A remaining at right angles to the tongue or pole. The gangs tend, of course, to point forward in the direction in which they are traveling, which is substantially parallel with the tongue or pole, so that the gangs tend to stay at right angles to the gang-arch A, as shown in Fig. 2. The rods 30 and springs 32 tend, also, to keep the gangs parallel with the pole or tongue and at right angles to the gang-arch A, for as soon as the gangs are swerved to one side the springs 32, which are compressed, will immediately exert sufficient pressure to very soon bring the gangs back into normal position. For this reason, therefore, when the rear end of the tongue or pole C is swung to one side, causing the wheels and main frame to skew relatively to the tongue or pole, the rods 30 and springs 32 tend to swerve both gangs sideways to keep them parallel with the tongue or pole.

In Figures 7 and 8, the pivotal connection 35 is shown between the axle and the casting or bar j, whereby the seat-frame J is supported upon the axle. Preferably, as shown, this connection consists of a socket 39 on the bottom of the bar j, and a bracket 40 suitably clamped upon the axle and provided at its top with rounded portion 41 which engages and turns in the socket 39, a vertical bolt 42 extending through the bar j and the portion 41 to form the pivotal connection. With this construction, the seat-frame J can turn easily on its fulcrum-like connection 35 with the axle, in the manner explained.

From the foregoing, it will be seen that a seat-controlled steering-arrangement is provided for swerving or veering the machine to either side, thereby to prevent the gangs from running over the corn, as will be readily understood, and so that the machine as a whole may follow the desired line of travel. The seat-frame serves as a lever, and thus instrumentalities are provided and arranged to be operated by the lateral movement of the seat to skew the wheels in either direction, the machine being steered to the left when the seat swings to the right, and the machine being steered to the right when the seat swings to the left, and the gang over which the foot-control is being exercised being shoved over in a direction opposite to that in which the seat is swung. If a gang is pushed over to the left, the reaction against the seat serves instantly to steer the machine over to the left, and a similar effect is produced when the other gang is pushed over to the right, for in such case the machine is immediately steered to the right. The gangs always remain parallel with the tongue, and the rear ends of the gangs are positively swung well over to the left or the right. If it is desired to swerve the machine to the right, the rear ends of the gangs will be swerved or swung over to the right, by movement of the seat to the left; and vice versa, the swinging of the seat to the right will swing the rear ends of the gangs to the left, as shown in Fig. 2. Thus, the weight of the driver in the seat is utilized for guiding the machine in the desired manner, and also to swing the gangs in the desired direction.

It will be seen, therefore, that in the construction and organization thus provided, the vehicle wheels skew about a common axis, relatively to the tongue or pole, which common axis is provided by the pivot 7 at the forward end of the main frame. It will also be seen that the gang-arch A or transverse supporting member is braced on the tongue, instead of on the main frame, and is thus held in absolutely fixed relation to the tongue or pole, so that this gang-arch not only does not turn about a vertical pivot, but does not swing forward and back at its lower ends relatively to the tongue. Also, the front end of the seat-frame is held down by its direct connection (36 and 37) with the rear end of the tongue, and is thus held by the latter against tilting upward. In this way the weight of the gang-arch A keeps the seat frame J from tilting upward at the front end thereof, and the weight of the gang-arch is also supported on the frame by the pendulums 10, as explained, so that the tongue and gang-arch resist the tendency of the seat frame to tilt upward at its front end.

The links 10 or pendulums, as they are often called, serve to keep the gang-arch A

and main frame E in horizontal relation to each other, so that the tongue cannot roll sidewise relative to said frame. This means, of course, that the gang-arch A cannot tilt 5 downward at either end, relative to the main frame, so that the gangs are maintained at the same depth, and at the same time the pole is prevented from tilting longitudinally relative to the main frame. While the 10 pendulums 10 are preferable for this purpose, it will be understood, of course, that any suitable means can be employed to accomplish this object, and that the invention is not limited to the exact construction 15 shown and described for this purpose.

It will be understood, of course, that the rods 30 can be left off, if such is necessary or desirable, so that the gangs will be free to swing sidewise relative to the tongue. 20 On the other hand, if desired, the springs 32 can be omitted, and the nuts on the rods 30 which bear against these springs (see Fig. 5) can be brought up tight against the brackets 31, thereby absolutely resisting all 25 lateral movement of the gangs relative to the tongue.

With the construction shown and described, which is illustrative of the invention, it will be seen that the long tongue or 30 pole C controls the two gangs, so that the latter are forcibly swung to either side to maintain them in alinement with the tongue—that is to say, to keep the draft line of 35 each gang parallel with the tongue, whereby 30 the tongue and draft arch and gangs constitute a structural unit to which the wheeled body frame is pivoted at its front end. Thus the tongue and draft arch A together 40 with the two gangs are practically independent of the body frame, for while the pendulums 10 support the gang arch on the body frame, in the manner explained, it is apparent that these pendulums exercise no 45 control over the gang arch when the body frame and wheels are skewed, or when the direction of the tongue or pole is changed. In other words, the gang arch and the gangs are controlled practically entirely by the tongue, without interference by the wheeled 50 body frame, and the driver controls the tongue through the medium of the seat frame, and through the medium of a pivot between the tongue and the forward end of the main body frame.

55 What I claim as my invention is:—

1. In a cultivating machine, a pair of vehicle wheels, a tongue extending forward and having its rear end indirectly supported by said wheels, a transverse member on said 60 tongue, means to maintain said member at a fixed angle transversely of said tongue, a pair of cultivator-gangs suitably connected with said member and disposed between said wheels, a seat supported for lateral movement relatively to the tongue and arranged

in position to permit foot-control over said gangs by the driver occupying said seat, and instrumentalities operated by lateral movement of said seat during said foot-control to skew said wheels about a common axis relatively to the tongue. 70

2. In a cultivating machine, a pair of vehicle wheels, a tongue extending forward and having its rear end indirectly supported by said wheels, a pair of cultivator-gangs 75 having connection with said tongue and disposed between said wheels, means to keep the gangs parallel with the tongue, a seat mounted for lateral movement and arranged in position to permit foot-control over said gangs by the driver occupying said seat, and instrumentalities operated by movement of said seat during said foot-control to skew said wheels about a common axis relatively to said tongue, said wheels having an axle 80 provided with a main frame which extends forward and has pivotal connection with said tongue to provide said axis, so that said main frame and tongue have lateral swinging motion relatively to each other, and said 85 instrumentalities including a seat-frame extending rearward to support said seat, said seat frame being pivotally connected with the top of said axle to turn about a vertical axis, and the forward end of said seat-frame 90 being connected to and held down by the end of said tongue in rear of the pivoted front end of said main frame.

3. In a cultivating machine, a structure as 100 specified in claim 2, said tongue being provided with a gang-arch connected at its lower ends at opposite sides to the front ends of said gangs, said arch being movable relatively to the main frame and means to permanently hold said gang-arch at right angles 105 to said tongue.

4. In a cultivating machine, a pair of vehicle wheels, a tongue extending forward and having its rear end indirectly supported by said wheels, a pair of cultivator-gangs 110 having connection with said tongue and disposed between said wheels, a seat mounted for lateral movement and arranged in position to permit foot-control over said gangs by the driver occupying said seat, and instrumentalities operated by movement of said seat during said foot-control to skew said wheels about a common axis relatively to said tongue, the connection between said 115 gangs and said tongue including a gang-arch supported by the tongue and braced thereon to remain at right angles thereto during the operation of said instrumentalities.

5. In a cultivating machine, a pair of vehicle wheels, a tongue extending forward and having its rear end portion indirectly supported by said wheels, a pair of cultivator-gangs having connection with said tongue 125 and disposed between said wheels, means to 130

- keep the gangs parallel with the tongue, so that the gangs are controlled by and swing with the tongue, a seat mounted for lateral movement and arranged in position to permit foot-control over said gangs by the driver occupying said seat, and instrumentalities operated by movement of said seat during said foot-control to skew said wheels relatively to said tongue, said instrumentalities including an element arranged to support said seat and fulcrumed between its ends to serve as a lever for controlling the tongue to swing the rear ends of the gangs laterally.
6. In a cultivating machine, a pair of vehicle wheels, a tongue extending forward and having its rear end indirectly supported by said wheels, a pair of cultivator-gangs having connection with said tongue and disposed between said wheels, a seat mounted for lateral movement and arranged in position to permit foot-control over said gangs by the driver occupying said seat, and instrumentalities operated by movement of said seat during said foot-control to skew said wheels relatively to said tongue, said wheels having an axle provided with a frame which has a pivotal connection with said tongue, so that said axle and frame and wheels all skew together relatively to said tongue, said axle and frame being permanently held at right angles to each other, the connection between said gangs and said tongue including a gang-arch supported by the tongue and held at right angles thereto, and said instrumentalities including a seat-frame extending rearward from said tongue to said seat, said seat-frame having a vertical pivot on said axle and a hinge connection with the rear end of said tongue, said hinge connection being supported entirely by the tongue and seat-frame, so that lateral movement of said seat skews said seat-frame relatively to said axle and thereby skews said axle in the same direction relatively to said tongue.
7. In a cultivating machine, a structure as specified in claim 6, in combination with means including springs to yieldingly maintain said gangs parallel with said tongue, so that when the tongue swings to either side the rear ends of the gangs will swing to the opposite side.
8. In a cultivating machine, a structure as specified in claim 1, in combination with means tending to maintain said gangs parallel with said tongue and at right angles to said member when the seat is swung laterally in either direction.
9. In a cultivating machine, a pair of vehicle wheels, a tongue extending forward and having its rear end supported by said wheels, a pair of cultivator-gangs having connection with said tongue and disposed between said wheels, a seat mounted for lateral movement and arranged in position to permit foot-control over said gangs by the driver occupying said seat, and instrumentalities operated by movement of said seat during said foot-control to skew said wheels about a common axis relatively to said tongue, said instrumentalities including a gang-arch held rigidly in fixed relation to said tongue, said means being disposed in rear of said gang-arch, and said instrumentalities including a seat-frame pivoted in rear of said means.
10. In a cultivating machine, a structure as specified in claim 1, said instrumentalities including a main frame pivoted on said tongue in front of said transverse member, and said main frame having laterally swinging pendulums to maintain said member a distance below, together with rigid braces extending from the tongue to said member, whereby said member in fixed relation to the tongue is movable therewith relatively to the main frame.
11. In a cultivating machine, a pair of vehicle wheels, a tongue extending forward and having its rear end supported by said wheels, a pair of cultivator-gangs having connection with said tongue and disposed between said wheels, means to keep the gangs parallel with the tongue, a seat mounted for lateral movement and arranged in position to permit foot-control over said gangs by the driver occupying said seat, and instrumentalities operated by movement of said seat during said foot-control to skew said wheels about a common axis relatively to said tongue, said instrumentalities including an axle for said wheels and a seat-frame pivoted at a fixed point on said axle and hinged at its forward end directly to the rear end of said tongue in front of said axis.
12. In a cultivating machine, a pair of vehicle wheels, a tongue extending forward and having its rear end indirectly supported by said wheels, a pair of cultivator-gangs having connection with said tongue and disposed between said wheels, a seat mounted for lateral movement and arranged in position to permit foot-control over said gangs by the driver occupying said seat, and instrumentalities operated by movement of said seat during said foot-control to skew said wheels about a common axis relatively to said tongue, said wheels having an axle provided with a frame pivoted on said tongue, the connection between said gangs and tongue including a gang-arch on the rear end of the tongue, braces extending forward from the lower ends of each gang-arch to said tongue, so that the gang-arch is rigid with the tongue, and vertically.

disposed links pivotally connecting the sides of said frame with the lower portions of said gang-arch.

13. In a cultivating machine, in combination a structure as specified in claim 1, said wheels having an axle provided with a frame pivoted on said tongue, together with rigid bracing means for said member, so that said member in fixed relation to the tongue is movable therewith relatively to the frame, and said frame having manually operated means for raising and lowering said gangs, said axle being mounted to rock in bearings on the rear end of said frame, and links to connect said manually operated means with said axle, so that raising of said gangs causes said axle to tilt forward and backward, said frame having pendulums to maintain said member a distance below.
14. In a cultivating machine, a pair of vehicle wheels, a main frame supported by said wheels, a tongue extending forward and having its rear end supported by said frame, a pair of cultivator-gangs having connection with said tongue and disposed between said wheels, a seat mounted for lateral movement and arranged in position to permit foot-control over said gangs by the driver occupying said seat, and instrumentalities operated by movement of said seat during said foot-control to skew said wheels and frame relatively to said tongue, the connection between said gangs and said tongue including a gang-arch, and said tongue being equipped with draft-devices connected to the lower ends of said gang-arch, so that the draft is communicated directly to the forward ends of said gangs, each gang being pivoted to swing up and down relatively to said gang-arch, means on said tongue to hold said gang-arch against movement relatively thereto, and means on said main frame to raise and lower said gangs.

15. In a cultivating machine, a frame provided with vehicle wheels, a tongue having its rear portion pivotally connected with said frame, so that said frame and tongue swing relatively to each other about a vertically disposed axis, cultivator gangs disposed between said wheels, an element rigid with said tongue to support the forward ends of said gangs, and means to connect the gangs with said element.

16. In a cultivating machine, a structure as specified in claim 15, in combination with swinging connections spaced apart and interposed between said frame and said element to prevent said tongue from rolling sidewise relatively to said frame, said tongue having braces which extend in front of said swinging connections to the outer ends of said element, whereby this element is held in fixed relation to the tongue.

17. In a cultivating machine, a structure as specified in claim 15, in combination with

a connection between said element and said frame to prevent longitudinal tilting of said tongue and its said rigid element relatively to said frame, while permitting said tongue and rigid element to swing in unison about 70 said vertical axis.

18. In a cultivating machine, a structure as specified in claim 15, in combination with means to prevent said frame from tilting up and down relatively to said element which is rigid with the tongue.

19. In a cultivator machine, a structure as specified in claim 1, in combination with a main frame, and pendulum rods hung on said frame and connected at their lower ends to said transverse member to prevent the tongue from tilting up and down relatively to said main frame, and rigid braces for said member which extend to the tongue in front of said pendulums.

20. In a cultivator, the combination of a tongue, a gang arch, means to hold the gang arch in fixed position on said tongue, cultivator gangs connected to said gang arch, a main frame, a pivotal connection between the tongue and the main frame, so that the tongue may swing laterally, devices on the main frame to raise and lower the gangs relatively to the tongue, and wheels to support the main frame.

21. A structure as specified in claim 20, said means comprising braces converging upwardly from the ends of the gang arch to said tongue.

22. In a cultivator, the combination of a tongue, a gang arch secured in fixed relation on said tongue, cultivating gangs connected to said gang arch, devices to raise and lower the gangs relatively to the tongue and arch, and a wheeled body frame to support said 105 devices and said tongue.

23. In a cultivator, the combination of the following eleven instrumentalities, to-wit: (1) a forwardly extending tongue or pole, (2) a gang-arch, (3) braces converging from the lower portions of said arch to said tongue, (4) a main body frame, (5) an axle and wheels to support said body frame, (6) a pivotal connection between said body frame and said tongue, whereby the tongue 110 is adapted to swing laterally relatively to said frame, (7) cultivator gangs disposed between said wheels, (8) means for connecting the forward ends of said gangs to the gang-arch, (9) provisions for keeping the gangs parallel with the tongue, so that the gangs and the tongue always extend in the same direction, (10) foot pieces on the rear ends of said gangs, (11) and a seat suitably mounted in position to enable the driver to 115 reach said foot pieces.

24. In a cultivator, the combination of a tongue, a pair of gangs, instrumentalities through which the tongue is operative to control and swing the gangs laterally to 130

maintain the line of draft of each gang parallel with the tongue, and a wheeled body frame pivoted at its front end on the tongue, so that the frame and tongue swing about a 5 vertically disposed axis relatively to each other.

25. A structure as specified in claim 24, said instrumentalities comprising a gang arch rigidly mounted on the rear end of the 10 tongue, in combination with laterally swinging pendulums to support the gang arch on the body frame, the tongue and gang arch being unconnected with the wheeled body frame except through the medium of said 15 axis and said pendulums.

26. In a cultivator, the combination of a

tongue, a pair of gangs, instrumentalities through which the tongue is operative to control and swing the gangs laterally to maintain the line of draft of each gang parallel with the tongue, said gangs being connected to swing up and down relatively to said tongue, means for raising and lowering the gangs about a transverse axis held in fixed relation to the tongue, and a wheeled 25 body frame pivoted at its front end on the tongue, so that the frame and tongue swing about a vertically disposed axis relatively to each other.

Signed by me at Chicago, Illinois, this 18th day of November, 1916.

ALVARO S. KROTZ.
